UNITED STATES PATENT OFFICE.

ALBERT FRANK WESTLUND, OF INDIANAPOLIS, INDIANA, ASSIGNOR TO THE PREST-O-LITE COMPANY, INC., OF INDIANAPOLIS, INDIANA, A CORPORATION OF NEW YORK.

FLASH CHECK FOR ACETYLENE-GAS TANKS.

1,407,610.

Specification of Letters Patent. Patented Feb. 21, 1922.

Application filed August 13, 1918. Serial No. 249,707.

To all whom it may concern:

Be it known that I, **ALBERT FRANK WEST-LUND**, a citizen of the United States, residing at Indianapolis, Marion County, and State 5 of Indiana, have invented and discovered certain new and useful Improvements in Flash Checks for Acetylene-Gas Tanks, of which the following is a specification.

My said invention consists in certain improvements in a flash or back fire check for acetylene gas lines of that type forming the subject matter of application No. 138,659, filed Dec. 23, 1916, by myself, jointly with Henry Sidney Smith, its purpose being to provide a check of the type referred to in which the flash arresting construction is of unitary form, as mounted in a cartridge casting, whereby it may be readily removed and refilled, and possessing other advantages, all of which will be hereinafter more fully described and claimed.

Referring to the accompanying drawings which are made a part hereof, and on which similar reference characters indicate similar parts.

Figure 1 is a view in elevation of the upper end of an acetylene gas tank of a common type, provided with an outlet fitting or valve, and showing a pipe or hose connected therewith, such as is commonly employed to supply tools with acetylene gas for cutting, welding, lighting and other purposes, the casing of said outlet fitting or valve embodying the flash arrestor forming the subject matter of my said invention.

Figure 2, a central section through the fitting and adjacent parts,

Figure 3, a view illustrating the parts composing the flash check in disassembled relation,

Figure 4, a view of a modified form, and Figure 5, a view illustrating an arrange-

ment and apparatus wherein a battery of tanks are employed.

Said tank A is provided with a collar 10 around a screw-threaded perforation in its top, in which the valve casing 11 is connected. The lower end of casing 11 is

formed with an interiorly screw-threaded socket into which a perforated plug 50 is inserted, a chamber 51 being provided above 55 said plug. The valve casing 11 has a screw-threaded socket 12 for connection with the tube fitting B and is formed with a central aperture 13 which is controlled by a needle valve 14 mounted in a perforation intersecting said perforation 13 at an angle as shown. Said needle valve 14 is formed on the end of a screw-threaded stem and adapted to be adjusted by turning said stem in the usual manner. The plug 50 in the lower end of 60 valve casing 11 has a central perforation 52 and depends a distance below said casing, with a tapered annular channel in said casing surrounding the upper end of its depending portion. The cartridge shell 15 is 70 tapered correspondingly at its upper end and screwed onto said depending portion, forming a tapered joint, as shown in Figure 2, thus holding said cartridge securely in place when the parts are assembled. The 75 lower end of the cartridge shell is closed or formed with the bottom in piece with its sides and has a concave upper surface. A recess is formed in the lower end of said cartridge shell and numerous perforations 80 lead through said bottom as shown. A screen basket 18 is mounted therein to prevent dust or dirt from passing into the casing 15. A disc or plate 19 of lead or other soft material is mounted on the top of the 85 concave bottom formed with a series of radial notches spaced around its edge and cutting back an appropriate distance toward its center through which the gas may pass when flowing from the tank into the chamber above the cartridge shell. A basket screen 20 may also be mounted at this end of the device. Above the disc 19 is a series of strainer discs 21 composed of strainer cloth, preferably of fine wire mesh. On top 95 of said strainer discs is mounted a quantity of aluminum shavings 22, which are found to possess certain advantages over the lead balls shown in the above mentioned application, although lead balls are perfectly practical for the purpose. Above the aluminum shavings or turnings are another series of strainer discs 23 and above said discs a plate 24 formed with numerous perforations. 100

The soft plate 19 rests at its edges upon the edge of the bottom of the cartridge, said bottom being concaved or tapered toward the center from its edges providing a chamber beneath said plate 19 into which the gas can flow from the tank through the perforations in the bottom of the cartridge and from which chamber the gas passes through the radial notches around the edge of said plate 19, through the strainer discs 21, through the mass of aluminum shavings 22, through the strainer discs 23 and through the perforations in disc 24 into a chamber 25, formed by a recess in the head plate 26 of the cartridge, and from thence through the central perforation in said head plate and plug 50 to chamber 51, and from thence through the central perforation 13 to the tube B, by which it is conducted under the regulation provided by valve 14 to the cutting, welding or other tool with which it is to be used.

The cartridge shell 15 is preferably of brass or hard metal as is also the head 26 and the plate 24. Head 26 is soldered or otherwise securely secured in place.

As explained in the application before referred to, in the use of acetylene gas in connection with cutting and welding tools, torches, etc., it occasionally occurs that because of over-heating of the torch employed, or for some other reason, a back flash or back fire occurs. This back fire may travel through the length of the hose and through the regulator in the valve casing and through the valve to the interior of the tank. The violence of the back fire or back flash may result in a local breaking down of the porous filling employed in the dissolved acetylene cylinder and thus forms a pocket which being filled with compressed acetylene gas may result in an explosion. With the construction of back flash arrestor herein shown and described, in the event of a back flash the pressure upon the washer or plate 19 transmitted through the other parts, immediately causes said plate 19 to buckle down upon the top surface of the bottom of the cartridge, seating said plate over the perforations and causing the soft metal to extrude into said small openings, and seal them against the passage of any gas or fire, thus protecting the gas in the tank and avoiding the danger of an explosion. I have found by experiments that when a back flash or back fire occurs, two waves proceed from the point of ignition, one a thermal wave, and the other a pressure wave. The pressure wave precedes the thermal wave throughout the explosion chamber and thus reaches the flash arrestor or soft plate 19 first. On account of the resistance to the flow of gas through the flash arrestor filling the pressure wave causes the aluminum shavings to become tightly packed and as the pressure increases in intensity the

lead disc is extruded into the small perforation in the bottom of the cartridge just beneath it. The thermal wave follows and comes in contact with the tightly packed aluminum shavings and the heat of this wave is dissipated to such an extent that the temperature of the explosion is lowered below the ignition point of decomposition.

The construction in Figure 4 will be readily understood from the foregoing description, it being merely a different type of fitting adapted to be inserted at any desired point in the supply line, as indicated in Figure 5, instead of being formed in the body of the valve itself.

In Figure 5, I show a battery of gas tanks, and any number may be used instead of the two shown, each tank connected to a header 30, from which the supply tube 31 leads to the tool. A flash check of my improved construction may be provided in the outlet fitting or valve of each tank, and if desired, fitting of the form shown in Figure 4 may be provided at points 32, where the cylinders connect into the manifold, or at any other points in the supply line at which it is desired to arrest a flash or back fire.

As indicated in Figure 2, the flash arrestor is mounted mainly within the tank, below its top, in an appropriate chamber in the fitting, and is entirely removed from danger of being tampered with by a user or others.

Having thus fully described my said invention, what I claim as new and desire to secure by Letters Patent, is:

1. A flash check or arrestor for acetylene gas supply lines comprising a cartridge shell interposed in the path of the gas with its ends formed with perforated closures, the lower end or bottom being concave, a soft ductile plate with normally flat surfaces mounted on said bottom and having notches in its edges, and means interposed between said soft plate and the head of the cartridge for receiving the back pressure and causing said soft plate to collapse to conform to the concave bottom and cover and seal the perforations therein under the shock caused by an explosion, substantially as set forth.

2. A flash check for an acetylene gas supply line comprising a cartridge shell mounted in said line and having perforated ends rigidly mounted therein, a collapsible plate of ductile material adapted to cover and extrude under pressure into the perforations in one end, and porous substance between said plate and the other end for receiving and transmitting the pressure to said collapsible plate when an explosion occurs, substantially as set forth.

3. A flash arrestor or check for an acetylene gas supply line comprising a soft plate interposed between the tank outlet and the point of use in a position to receive the back pressure caused by the back fire and be com-

pressed to cover and close the outlet from said tank, another plate rigidly supported spaced therefrom, and aluminum shavings interposed between said soft plate and said 5 other plate, substantially as set forth.

In witness whereof, I have hereunto set my hand and seal at Indianapolis, Indiana,

this 7th day of August, A. D. nineteen hundred and eighteen.

ALBERT FRANK WESTLUND. [L. S.]
